H. W. NEAL

HEAT ACCELERATOR FOR HOT AIR FURNACES

Filed Feb. 5, 1923

Patented Aug. 21, 1923.

1,465,309

UNITED STATES PATENT OFFICE.

HARRY W. NEAL, OF INDIANAPOLIS, INDIANA. ASSIGNOR OF ONE-HALF TO HALL-NEAL FURNACE COMPANY, OF INDIANAPOLIS, INDIANA, A CORPORATION OF INDIANA.

HEAT ACCELERATOR FOR HOT-AIR FURNACES.

Application filed February 5, 1923. Serial No. 616,907.

To all whom it may concern:

Be it known that I, HARRY W. NEAL, a citizen of the United States, residing at Indianapolis, in the county of Marion and State of Indiana, have invented new and useful Improvements in Heat Accelerators for Hot-Air Furnaces, of which the following is a specification.

This invention relates to improvements in furnaces for supplying hot-air for heating houses of the same character as patented to me in United States patent issued January 2, 1923, No. 1,440,486, and the object of this invention is to increase the radiating surface of furnaces already built under prevailing methods without including the invention above patented to me, whether said furnaces have been assembled or not.

Another object is to embody the invention in a device as a new article of manufacture, that may be sold to the trade or direct to the consumer, and placed in the hot-air conductors of any furnace on the market by any person without the aid of a skilled mechanic.

I accomplish the above, and other objects which will hereinafter appear, by the mechanism illustrated in the accompanying drawing, in which—

Fig. 1, is a view in front elevation and partial vertical section of a common type of steel dome heating furnace with my invention operatively installed. Fig. 2, is a perspective view of my invention apart from the furnace and pipe in which it is used. Fig. 3, is a view of the end remote from the furnace, of the device shown in Fig. 2, and Fig. 4, is a vertical section of the casing of a common type of furnace in which the radiating chambers are made of cast iron instead of out of sheet metal as in Fig. 1.

Like characters of reference indicate like parts in the several views of the drawing.

My invention is applicable to any type of domestic heating furnace on the market, the two patterns shown in the drawings being selected merely to illustrate the manner of use.

In the drawing, 5 represents the dome or chamber for collecting the heat from the fire-pot below, and for heating air by contact and radiation that is to be conveyed to the rooms of the house for heating them. Surrounding this is a sheet-metal casing 6, of usual form, having an oblique portion 7,

from which upwardly oblique hot-air conductor tubes 8 radiate in the usual manner.

The invention here comprises a plurality of thin sheet-metal plates 9, united to form a unitary structure, by means of a number of bolts 10, passing transversely through the plates and through spacing cylinders 11, here shown as short lengths of iron pipe.

The plates, at one end of the unit, are beveled or curved or otherwise suitably shaped to conform closely with the contour of the top of the dome, against which said ends make a bearing contact when in use, in order that the heat from the heated surface of the dome may be conducted to the metal plates and through them and discharged by radiation from the extended radiating surfaces which the numerous plates provide.

The widths of the plates 9 vary from a middle maximum to such a minimum for the outside plates as will permit the unit to be slidingly assembled through the thimble 13 of the furnace, and also to enter the adjacent section of the conductor tube 8, in the manner substantially as shown.

One of the above-described units is placed in each hot-air conductor tube 8 of the furnace.

In the modification shown in Fig. 4, the lower ends of the plates of the inserted unit rest upon the cast radiating chambers 15.

The number of plates in a unit, the number and location of the bolts uniting them, the shape of the furnace-contacting ends of the plates, etc., may be varied without departing from the spirit of the invention and I therefore do not desire to be held to the precise form shown or any more than is required by the appended claims.

I claim:

1. In combination with a hot-air furnace having a radiating chamber in communication with the fire-pot, means comprising a plurality of straight parallel sections retained in a unit of varying width widest toward the middle plate with air-spaces between the sections, the ends of said sections conforming approximately with the shape of the walls of the chamber and contacting therewith.

2. In combination with a hot-air furnace having a radiating chamber, means comprising a plurality of straight parallel metal plates retained in a unit of varying width

widest toward the middle plate with air-spaces between the plates, an end of each of said plates conforming approximately with the shape of the chamber walls and contacting therewith.

3. In combination with a hot-air furnace having a radiating chamber, means comprising a plurality of straight parallel metal plates retained in a unit of varying width widest toward the middle plate with air-spaces between the plates, an end of each of said plates conforming approximately with the shape of the chamber walls and contacting therewith, said unit being removable from the furnace.

4. In combination with a hot-air furnace having hot-air conducting tubes, means comprising a plurality of straight parallel metal plates retained in a unit widest toward the middle plate with air-spaces between the plates and located close to the furnace in said tubes.

5. In combination with a hot-air furnace having a radiating chamber and hot-air conducting tubes, means comprising a plurality of straight parallel metal plates decreasing in width from a middle one of maximum width retained in a unit with air-spaces between the plates and located in the tubes in contact with the chamber.

6. In combination with a hot-air furnace having a radiating chamber and hot-air conducting tubes, means comprising a plurality of substantially rectangular metal plates retained in a unit with air-spaces between the plates and located in the tubes with one of the short sides of each plate in contact with the chamber, said plates varying in width and assembled with the narrower ones on each side of and correspondingly remote from a middle plate of maximum width.

Signed at Indianapolis, Indiana, this the first day of February, 1922.

HARRY W. NEAL.
